UNITED STATES PATENT OFFICE.

BERNHARD DREYER, OF PHILADELPHIA, PENNSYLVANIA, ASSIGNOR TO
WILLIAM H. FRENCH, OF SAME PLACE.

DESIGN FOR CENTER-PIECE FOR CEILINGS.

Specification forming part of Design No. 6,711, dated June 24, 1873; application filed May 31, 1873.

To all whom it may concern:

Be it known that I, BERNHARD DREYER, of the city and county of Philadelphia, in the State of Pennsylvania, have invented and produced a new and original Design for a Center-Piece for Ceilings; and I do hereby declare the following to be a specification thereof.

The nature of my design is shown in the accompanying engraving, which forms a part of this specification, and represents so much of a center-piece, made according to the said design, as is necessary to show my invention.

The leading features of this design are as follows: The figure A B C, whose perimeter consists of straight and curved lines, disposed substantially as shown, and incloses the incised work D D, radiating from the center. The circular molding E between two ogee moldings, F, diametrically opposite to each

other. The honeysuckle G in the space between the circular and ogee molding.

The details of the ornamentation may be varied.

What I claim as my invention, and desire to secure by Letters Patent of the United States, is—

1. The figure A B C and incised work D D inclosed therein, substantially as shown and described.
2. The circular molding E between two ogee moldings, F, diametrically opposite to each other.
3. The honeysuckle G in the space between the circular molding E and ogee molding F.
4. The entire design, substantially as shown.

Witnesses: BERNHARD DREYER.

J. BONSALL TAYLOR,
W. H. ADDICKS.
